UNITED STATES PATENT OFFICE.

PETER F. SCHNEIDER, RAYMOND J. SCHNEIDER, AND WILLIAM F. BLAKE, OF DETROIT,
MICHIGAN.

WASHING MACHINE.

Application filed October 31, 1919. Serial No. 334,728.

To all whom it may concern:

Be it known that we, PETER F. SCHNEIDER, RAYMOND J. SCHNEIDER, and WILLIAM F. BLAKE, citizens of the United States, residing at Detroit, county of Wayne, State of Michigan, have invented a certain new and useful Improvement in Washing Machines, and declare the following to be a full, clear, and exact description of the same, such as will enable others skilled in the art to which it pertains to make and use the same, reference being had to the accompanying drawings, which form a part of this specification.

This invention relates to washing machines, and the object thereof is to provide an improved mechanism including what are termed vacuum cups reciprocable in a tub to force wash water through the clothing and relates particularly to the arrangement of a plurality of cups substantially equidistantly positioned about the center of the tub whereby the clothing is practically all subjected to the washing effect of the cups without necessity of revolving the tub or of altering the position of the cups about the center as has heretofore been done.

In previous known construction employing cups reciprocable to produce movement of the wash water through the clothing the cups have been turned about a center whereby all of the clothing being washed is subjected to equal washing action by the cups and such construction either in the turning of the cups or of the tub results in a winding of the clothes about each other. This undesired result is obviated in the present construction by use of a greater number of cups whereby the washing effect is substantially equally distributed through the entire quantity of clothing, the only movement of the cups being a reciprocable movement.

A further feature of the invention is involved in the construction whereby the cups are arranged in pairs on opposite sides of the tub and are reciprocated in alternate relation, resulting in a more rapidly operating machine than with previous types. An additional object of the invention is to provide a false bottom preferably supported centrally of the tub whereby the downward operation of the cups on one side tends to depress that side and to raise the other side thereby fluffing the clothing in the water.

A further object is to provide a false bottom having perforations and adapted to be raised from the bottom to near the top whereby the clothes may drain prior to being passed through the wringer and obviating the necessity of the operator picking the clothes out of the heated water. These objects and the other minor objects of the invention and the several novel features of construction thereof are hereinafter more fully described and claimed and shown in the accompanying drawings in which—

Fig. 1 is a vertical section showing our improved washing machine.

Fig. 2 is a plan view thereof.

Fig. 3 is a side elevation of the machine showing the operating mechanism.

Fig. 4 is an elevation of mechanism employed in reciprocating the cups.

Fig. 5 is a detail illustrating the mechanism employed in operating the wringer.

Fig. 6 is an elevation in detail showing the clutch mechanism for independently applying the power at will to the wringer or to the washer.

In the embodiment of the invention herein shown, the tub is indicated at 1 which is preferably of metal and within the tub are two pairs of vacuum cups 2 and 3 positioned on opposite sides of the center line, the pairs of cups 2 being supported on a yoke 4 and the pairs of cups 3 being supported on a yoke 5. Preferably a cup 2 is spaced from its companion a distance approximately equal to that of its spacing from a cup 3 so that the four cups are substantially equidistantly positioned about the vertical axis of the tub. These yokes are downwardly inclined as will be understood from Fig. 1 and detachably connected at the end 6 to the upper end of the vertical reciprocating rods 7 and 7^a respectively which rods are reciprocable in bearings provided therefor respectively on opposite sides of the tub.

The shafts or rods 7 and 7^a are preferably reciprocable in alternate relation and any approved mechanism may be employed to so reciprocate the rods, the mechanism shown being a horizontal shaft 8 having a worm gear 9 thereon operated by means of a worm 10 on the shaft of the motor 11, the particular arrangement of the said construction being hereinafter more fully described. On opposite ends of the shaft are

provided cams 12 and 13 similar in form but oppositely disposed. On each rod 7 and 7^a is mounted a pin or roller 14 in each case riding on the periphery of the cam. These rods 7 and 7^a extend into bearing members 15 and 16 respectively so that the shaft is guided by the lower bearings and the bearings provided therefor within the tub and the cam rollers 14 are positioned between the bearings. A coiled spring 17 is provided for each rod which is a tension spring in the construction shown tending to draw the shafts and cups thereon downward in the position shown at the left of Fig. 1. By rotation of the shaft 8 and the cams 12 and 13 thereon the shafts 7 and 7^a are alternately raised as is shown at the right hand side of Fig. 1 and when so raised the springs 17 are placed under tension causing the roller to continuously ride in contact with the cam. By this construction the cups are raised from engagement with the clothing by the cams and are forced into contact with the clothing by the springs. By this arrangement no detrimental effect can result in operation when a greater quantity of clothing is accidentally piled beneath one or the other of the cups. If the cam members were of a construction producing a positive movement in both directions of the shaft 7 or 7^a an increased quantity of clothing would tend to cause a breakage or a pounding having a detrimental effect on the mechanism. By providing a movement of the cups that is yieldable in a downward direction such pounding or possible breakage is avoided.

The clothing is washed in the well known manner by forcing these cups which are termed vacuum cups onto the clothing immersed in the heated water and then downward movement causes water to be forced through the clothing and the succeeding upward movement tends to draw soapy wash water upward through the clothing and this continued movement backward and forward of the water through the clothing results in cleansing thereof. By arranging the cups to be operated in alternate relation to the load to which the motor is subjected is comparatively constant and uniform smoothness of operation results whereas, if both pairs of cups were moved upward and downward in unison the motor would be overloaded during a part of the said movement and be practically released from the load during the remaining part.

Preferably a false bottom 18 is provided in the tub having a series of perforations 19 of any approved form therein. Preferably this bottom has a peripheral upwardly extending flange 20 thereon shown by dotted lines in Fig. 1 which lies close to the inner wall of the tub and is short in length 65 to prevent the clothing from working off

from the said bottom into the interstice between the tub and the said bottom. This false bottom as shown in Figs. 1 and 2 is pivotally supported on a shaft 21 and when clothes are placed in the tub the alternate movement of the cups 2 and 3, rocks the false bottom on its pivot which fluffs the clothes and prevents them from remaining in a compact mass beneath either of the pairs of cups. The pairs of cups are detachably mounted on the ends of the shafts 7 and 7^a. By removal of the cups from the ends of these shafts, the false bottom may be lifted by the two handles 22 until clear of the water, whereupon the clothes supported on the said false bottom drain through the apertures therein and thus allow the operator to handle the clothes without immersing his hands in the hot water contained in the tub. To support the false bottom above the water in the tub, the rods 22 are provided with joints 27 at about the center thereof. When the bottom has been raised within the tub the handles or rods 22 are turned over the upper edge of the tub by means of the joints 27 and thereby the false bottom is supported in the raised position. As will be noted from the drawings, handles 23 and 24 are provided which operate companion clutches the handle 23 operating a clutch 25 which connects or disconnects the motor with the washing machine mechanism and the handle 24 operating a clutch 26 which connects or disconnects the motor with the wringer mechanism. Thus by use of these handles or levers, the washing machine or wringer may be operated at will or withheld from operation.

From the foregoing, it becomes evident that the device is very efficient in operation, is easily handled and accomplishes the objects desired.

Having thus briefly described our invention, its utility and mode of operation, what we claim and desire to secure by Letters Patent of the United States is—

1. In a washing machine, a receptacle substantially cylindrical in form, a pair of rods one on each side of the tub extending upward through the bottom thereof, a vacuum cup supported on each rod within the tub, guideways in the tub for the said rods, and power operated means beneath the tub for reciprocating the rods in alternate relation. 115

2. In a washing machine, a receptacle substantially cylindrical in form, a pair of rods one on each side of the tub extending upward through the bottom thereof, guide members for the rods within the tub, the upper end of which is above the normal level 125 of the water in the tub, a yoke attached to the upper end of each rod, each yoke having a laterally extending arm, a vacuum cup supported at each end of each arm, the cups being substantially in equidistantly spaced 130

relation about a center, and power actuated means beneath the tub adapted to alternately reciprocate the rods.

3. In a washing machine, a tub substantially cylindrical in form, vertically positioned rods on opposite sides of the tub extending upward through the bottom thereof, guide members within the tub through which the rods may reciprocate, a vacuum cup detachably supported at the upper end of each rod, and power-operated means beneath the tub for reciprocating the rods in alternate relation.

4. In a washing machine, a receptacle substantially cylindrical in form, vertically positioned rods on diametrically opposite sides of the interior of the tub extending upward through the bottom thereof, a framework for supporting the tub, guide members within the tub for each rod, guide members in the framework for the lower ends of the rods, a vacuum cup detachably connected to the upper end of each rod, and means for alternately reciprocating the rods.

5. In a washing machine, a tub substantially cylindrical in form, two pairs of vacuum cups in substantially equidistantly spaced relation about a center, a rod on

diametrically opposite sides of the tub to the upper end of each of which a pair of 30 cups is attached, the rods extending upwardly through the tub bottom, and means beneath the tub for vertically reciprocating the rods in alternate relation.

6. In a washing machine, a tub, a pair 35 of vertical reciprocable rods extending upward therewith through the bottom, said rods being on diametrically opposite sides of the tub, a yoke detachably connected to each rod and extending inwardly and downwardly at an angle to the rod, and vacuum cups attached to each yoke.

7. In a washing machine, a tub, a pair of 45 vertically reciprocable rods on opposite sides of the tub extending upward through the bottom thereof, a yoke detachably connected with each rod and consisting of an arm extending inwardly and downwardly from each rod at an angle and having a cross arm at the lower end, and a vacuum cup at each 50 end of the cross arm of each yoke.

In testimony whereof, we sign this specification.

PETER F. SCHNEIDER.
RAYMOND J. SCHNEIDER.
WILLIAM F. BLAKE.
